United States Patent Office

Des. 213,313
Patented Feb. 18, 1969

213,313

VEHICLE

Donald F. Haskin, 11416 Miranda St., North Hollywood,
Calif. 91601, and Max Becker, 14058 Valley Heart
Drive, Apt. 3, Sherman Oaks, Calif. 91403

Filed Apr. 22, 1968, Ser. No. 11,562

Term of patent 14 years

U.S. Cl. D14—3

Int. Cl. D12—08

FIG.—1

FIG.—2

FIG. -4

FIG. -5

FIG. -3

FIG. 1 is a perspective view of the front and right side of a vehicle showing our new design;

FIG. 2 is a perspective view of the rear and right side of the vehicle of FIG. 1;

FIG. 3 is a rear elevation view thereof;

FIG. 4 is a front elevation view thereof; and

FIG. 5 is a side elevation view thereof.

The dominant features of our design reside in the portion shown in full lines only.

We claim:

The ornamental design for a vehicle, substantially as shown and described.
